UNITED STATES PATENT OFFICE

THOMAS A. PEEBLES, OF MOUNT LEBANON, PENNSYLVANIA, ASSIGNOR TO JOHN M. HOPWOOD, OF DORMONT, PENNSYLVANIA

DRAFT CONTROL SYSTEM

Application filed June 19, 1931. Serial No. 545,425.

This invention relates, in general, to boiler furnaces and more particularly to the control of dampers and blowers therefor.

In the operation of boiler furnaces air for combustion is supplied either by forced or induced draft mechanisms, or by both forced and induced draft. In either case, motor driven fans are employed.

Practical experience has demonstrated that satisfactory control of the draft cannot be obtained by adjustments of fan or blower speeds only. The ordinary type of motor employed for such service is adapted to operate at only a few speeds between maximum and minimum, whereas the load carried by a boiler furnace at any instance may require a fan speed that lies between the speeds at which the motor will operate. If damper control is not used, it would only be possible to operate the boilers efficiently at a series of definite ratings depending upon the air or gas handling capacity of the fan when running at the speed available by the type of motor employed. This is an unsatisfactory condition.

There is a certain interval between the time a change in motor speed is initiated and the time the motor actually comes to the new speed, giving the fan or blower a new air or gas handling capacity. This interval should be reduced to the shortest possible time to prevent hunting of the motor regulating equipment, and this is best employed by employing damper control.

It is customary therefore to effect draft control by a combination of fan speed and damper regulation. An arrangement commonly employed includes an electric controller so arranged that when the damper or the regulator handling the damper reaches a predetermined open position, the speed of the fan motor will be increased. The increased speed of the fan increases the amount of air or gas handled and this amount exceeds the amount actually required, causing the regulator to reverse its direction of travel and find a new position in which the damper is nearer the closed position than it was before the fan was speeded up.

Further increases in load cause the damper

to open again finally reaching the point where the fan is speeded up to a higher predetermined speed. When the load on the boiler decreases and the damper is brought to a predetermined closed position, the electric controller operates to reduce the speed of the motor driving the fan. At this reduced speed the air handling capacity of the fan is less which requires a slight opening of the damper to give final regulation of the air required.

There are certain objections to arrangements for the control of fan speed and damper position as outlined above and may be pointed out as follows:

Assume that the boiler is operating at minimum load with the fan operating at minimum speed and the damper near its closed position. As the load on the boiler increases, the damper is gradually opened but a point is soon reached where further movement of the damper is not effective to increase the furnace draft. When the fan is running at a low speed, this position may be only 15 or 20 degrees of damper opening.

It will be apparent that if the duct in which the damper is placed is large enough to handle all the air or gas the fan can deliver when running at full speed, this duct will be very much larger than is required to handle the air delivered by the fan when running at minimum speed. The result is that a small movement of the damper gives all the regulation that can be secured while the fan is operating at low speed. It will be apparent that with the arrangement com-

monly used for this purpose it is necessary for the regulator to continue opening the damper until it approaches its wide open position before the speed of the fan will be increased. The result is that throughout a large portion of the stroke of the regulator no effective control of the damper will be obtained.

On the other hand, if the furnace is operating at its maximum load with the fan at full speed and the damper wide open and the boiler load drops off, the damper is gradually closed but no reduction in fan speed will take effect until the damper approaches its closed position. The result is that a com-

paratively low load might be carried by the boiler, but the fan will be operating at full speed. In this case a large amount of throttling takes place at the damper. The motor driving the fan is therefore operating at an excessive speed and load resulting of course in a loss of power which it is desirable to avoid.

An object of this invention, generally 10 stated, is to provide for maintaining the proper relation between the speed of a fan or blower and the position of the damper at which blower or fan speed changes will occur.

Another object of the invention is the provision of a damper and fan speed control so arranged that for each position of the damper the blower or fan will be operated at such a speed that the volume of air or gas handled thereby may be effectively regulated by 20 small adjustments in the damper position.

Other objects of the invention will, in part, be apparent and will, in part, be obvious from the following specification and the drawings forming part hereof.

25 The invention comprises the details of construction and the novel arrangement of circuits and apparatus as illustrated in the accompanying drawings in which:

Figure 1 is a schematic illustration of a 30 boiler furnace and apparatus for controlling or regulating the position of dampers and the speed of fan blowers utilized to supply and control the amount of air and gas supplied to and taken from the furnace;

35 Fig. 2 is an assembled view, partly in section, of a regulator embodied in the system shown in Fig. 1; and

Fig. 3 is a diagrammatic illustration of 40 circuits and apparatus employed for controlling the speed of the blower or fan motors shown in Fig. 1.

Throughout the drawings and specification like reference characters indicate like parts.

45 In Fig. 1 of the drawings a boiler furnace 1 is shown having forced and induced draft mechanisms 2 and 3, respectively. The steam generated by the boiler is delivered to the usual header H.

50 The forced draft mechanism comprises a blower or fan 4 driven by a variable speed motor 5, preferably an electric motor. The speed of motor 5 may be adjusted or varied by means of a controller 6 which is schematically illustrated in Fig. 3 of the drawings.

Blower or fan 4 blows or forces air into the furnace through a conduit 7 having a damper 8 therein. Damper 8 may be operated or adjusted from open to closed positions, or vice 60 versa by an actuating means 9. The type of actuating means illustrated may be a pressure responsive regulator arranged to respond to the pressure within the furnace combustion chamber. The furnace chamber pressure may 65 be transmitted to the pressure responsive ele-

ment of the actuating means 9 through a pipe or conduit 10.

As the pressure in the furnace rises and falls, damper 8 is so actuated that the opening thereof is either decreased or increased until the pressure within the chamber is restored to a predetermined value. For operating reasons it is desirable to maintain the aforesaid furnace pressure substantially constant.

In order that damper 8 may be effective, when adjusted to any position, to control the flow of fluid or air through conduit 7, the quantity flow of such air or fluid must be adjusted in proportion to the degree of damper opening, or in other words, in proportion to the position of the damper.

For example, if a large quantity or volume of air or fluid is flowing through conduit 7 and the damper is in its full open position, a small movement of the damper will materially decrease the flow of air through the conduit. On the other hand, if a small quantity of air or fluid is flowing and the damper is wide open, small movements of the damper towards closed position will have practically no effect upon the quantity of air flowing. In the latter case, the damper is ineffective to change the quantity of air flowing until it is practically in its closed position.

In order that damper 8 may be effective to change or regulate the quantity of air or fluid flowing when adjusted to any position whether such position be substantially the closed, the wide open, or any intermediate position, the quantity or volume of air flowing should be apportioned in accordance with the position of the damper.

In the present case, since blower 4 is a source of forced draft, the speed of the blower should be adjusted to deliver a large volume of air to the furnace when the damper is in or near its wide open position; a relatively small volume of air, when the damper is in or near its closed position; and intermediate volumes when the position of the damper is between the wide open and the closed positions. In other words, it is proposed to adjust the speed of the blower in substantially direct proportion to the degree of damper opening; or in accordance with the position of the damper. Stated in another way, it is proposed to so regulate the speed of the blower that it will deliver different quantities or volumes of air or fluid for different positions of the damper. In each case, the volume or quantity of fluid or air delivered will be so apportioned that small movements of or adjustments of the damper will have an appreciable regulating effect upon the volume flow of the air or fluid.

If the speed of the blower is varied or adjusted as indicated above, the quantity of air flowing for any given blower speed may be varied by small adjustments or changes in the position of the damper.

In order that, when the position of the damper is changed, either towards the closed or the open positions, the speed of the blower or fan may be changed in the same direction and in proportion to the change in damper position, actuating means 9 is provided with a circuit controlling device 11. Circuit controlling device 11 is so arranged that it may be moved bodily by the actuating means, when it has moved a predetermined amount, in either direction.

The circuit controlling device 11 governs the operation of motor controller 6 and is so arranged that, for any given position of the damper, the speed of motor 5 may be increased or decreased in response to small deviations in furnace pressure that may take place while the damper is in any particular position. For each position of the circuit controlling device 11, the blower motor is caused, by its controller 6, to operate at a different predetermined speed.

Since the pressure responsive actuating means 9 operates directly upon the damper, it will be apparent that the speed of the blower 4 will be adjusted to a value corresponding to the position, degree or amount of damper opening.

The induced draft mechanism 3 comprises a blower or fan 12 that is driven by a variable speed electric motor 13. Blower or fan 12 draws air and products of combustion from the furnace chamber through a conduit 14 having a damper 15 therein and discharges such air and products of combustion into a conduit 16 that is connected to the usual stack (not shown).

Damper 15 may be operated or adjusted by an actuating means 17 similar to the actuating means 9. Actuating means 17 may be arranged to respond to the demand for steam upon the boiler and to the pressure obtaining in the furnace chamber at the point where conduit 14 has communication therewith. Pressure from the furnace chamber in the region of conduit 14 may be communicated to a pressure responsive element of actuating means 17 through a conduit or pipe 18.

In order that the actuating means 17 may be so modified that it will adjust damper 15 by and in accordance with the demand for steam as well as in accordance with variations in pressure in the furnace uptake, a master regulator 21 is provided. Master regulator 21 is so arranged that it effects a reduction in pressure within bellows 19 when the steam pressure falls and the demand for steam increases and an increase in pressure within the bellows when the steam pressure rises and the demand for steam decreases.

Master regulator 21 comprises a pressure responsive or metering device 22 such as illustrated in United States Patent No. 1,371,243 granted March 15, 1921, to John M.

Hopwood and a master pressure sending relay 23.

Device 22 includes a weight arm 24 that is acted upon by a pressure diaphragm 25 in one direction and in the opposite direction by an opposing pressure diaphragm 26. Pressure diaphragm 25 is subjected to the steam pressure in header H of the boiler, whereas diaphragm 26 is acted upon by a constant pressure confined within a bellows or drum 26'.

Diaphragm 26 is of such shape, as described in said Patent No. 1,371,243, that the area thereof bearing on and in contact with a plate 27, interposed between said diaphragm and weight arm 24, varies as the pressure on diaphragm 25 varies. Thus, any movement of weight arm 24 will be directly proportional to the pressure acting on diaphragm 25, hence, directly proportional to the steam pressure in header H.

Master pressure sending relay 23 comprises a pressure responsive bellows 28 and a valve 29 having a valve plug 30 therein jointly controlled by the bellows and the weight arm 24.

Valve plug 30 has a valve stem 31 connected to one end of a floating lever 32, the other end of said lever being connected by a link 33 to weight arm 24.

Bellows 28 is provided with a push rod 34' the upper end of which is connected to floating lever 32 between the ends thereof, thus lever 32 may pivot about its connection with valve stem 31, its connection with link 33 or about its connection with push rod 34'. Bellows 28 operates against a spring 35' so that the amount it expands or contracts will be substantially directly in proportion to the pressure applied to the interior thereof. Valve 29 has a port which is connected to a pipe line 36' having therein a supply of fluid under pressure. Valve 29 also has an outlet port connected by a pipe 37' to a pipe line 38' whereby pressure variations may be communicated to bellows 19. Pipe line 38' is in communication with the interior of bellows 28 and the interior of bellows 19.

When the pressure in steam header H rises lever 24 moves clockwise, thereby turning floating lever 32 counterclockwise about its pivotal connection with push rod 34' thereby moving valve plug 30 downwardly until pressure flows from supply line 36' through pipe 37' to the interior of bellows 28 and the interior of pipe line 38'. The pressure so delivered causes bellows 28 to expand whereby floating lever 32 is turned clockwise about its pivotal connection with link 33 causing valve plug 30 to move upwardly and close the valve port to which pipe 37' is connected, thus shutting off further increase in pressure in bellows 28 and pipe line 38'. If the pressure in the steam header falls, the opposite action takes place, that is, valve plug 30 will rise causing pressure in pipe line 38'.

38' and bellows 28 to exhaust through pipe 37 and exhaust port 39' in valve 29 to the atmosphere, thereby reducing the pressure in bellows 28 and pipe line 38'.

5 As the pressure is reduced, spring 35' will cause the bellows 28 to collapse, thereby turning valve plug 30 to its neutral position in which position further exhausting of pressure from bellows 28 and pipe line 38' to the atmosphere is prevented until the pressure in the steam header falls again to a lower value.

In the present case, it is proposed to maintain the force acting on actuating means 17, as affected by the pressure in conduit 14, in equilibrium with the force acting thereon by bellows 19. If for any cause, this equilibrium is disturbed, means 17 will operate to adjust damper 15 until equilibrium is again restored.

20 In order that movements of the actuating means 17 caused either by the pressure acting through bellows 19 or the pressure acting through pipe line 18, or both, may be utilized to control the operation of motor 13 in accordance with the position of damper 15, a circuit controlling device 11' is provided. Circuit controlling device 11' operates in the same manner as circuit controlling device 11 and is arranged to be moved bodily by the actuating means 17 when it has moved a predetermined amount in either direction. Circuit controlling device 11' controls the operation of a motor controller 6' that is similar to controller 6. Controller 6' is 25 illustrated schematically in Fig. 3 of the drawings and operates to adjust the speed of motor 13.

In Fig. 2 of the drawings, regulating device or actuating means 17 is illustrated in 40 detail.

Devices 17 and 9 are, in the present case, identical except for the bellows 19, the bellows being omitted in device 9. Since these devices are otherwise identical, the description 45 of device 17 will be sufficient for both.

Device 17 comprises a pressure responsive element 34 and a fluid pressure motor or regulator 35.

The pressure responsive element comprises 50 a lever or beam 36 mounted on a fulcrum 37, and inverted bells 38 and 39 mounted at opposite ends of the beam. Bells 38 and 39 are partially immersed in liquid 40 contained in a tank 41 having a suitable cover 42. Bell 55 38 has an interior chamber 43 that is open at the top and closed at its bottom. An orifice 44 is provided in the bottom of chamber 43 in which a needle valve 45 is adjustably disposed.

60 Bell 39 likewise is provided with an interior chamber 47 having a needle valve orifice 48 and needle valve 49 in its bottom.

When bells 38 and 39 are at rest, fluid in the tank 41 will flow through the needle valves 65 55 into chambers 43 and 47 until the level of the

fluid therein is equal to the level of the fluid in the tank. If lever or beam 36 is caused to turn on its fulcrum, thereby raising one of the bells and lowering the other, the fluid in the bell which is being raised will gradually flow out through its needle valve, gradually decreasing the retarding effect of such fluid to upward movement of the bell. The bell on the opposite end of the lever which is being lowered and submerged, offers resistance to such movement and retards the turning of the lever. However, this retarding effect gradually decreases as the fluid from the tank flows through the needle valve associated with the bell being lowered and into the interior chamber thereof.

The damping or retarding effect of interior chambers 43 and 47 upon the movements of bells 38 and 39 is clearly disclosed in my U. S. Letters Patent No. 1,800,400 granted April 14, 1931.

The retarding effect of the interior chambers on the movement of bells 38 and 39 may be adjusted by means of the needle valves 45 and 49, respectively.

The interior of bell 39 has communication with pipe 18 and is therefore subjected to the pressure in conduit 14, whereas, the interior bell 38 has communication with the atmosphere through a pipe 50. The interior of bell 38 is therefore subjected to a constant pressure while the interior of bell 39 is under a pressure which may vary from time to time as the pressure in conduit 14 changes. In response to changes in pressure within bell 39, lever or beam 36 will turn in one direction or the other depending upon the direction of change in pressure. Movements of beam 36 are utilized to control the operation of fluid pressure motor or regulator 35.

Fluid motor or regulator 35 comprises a cylinder 52 having a piston therein (not shown) and a frame 53 carried by a piston rod 54 attached to the top face of the piston.

Motive fluid, such as compressed air, may be admitted to either side of the piston by means of a valve 56, the motive fluid entering the valve through an inlet port 57. Valve 56 has a valve stem 58 which, when moved downwardly and below the closed position of the valve, opens the valve to admit air or fluid under pressure to the cylinder at the bottom face of the piston; and when moved upwardly above the closed position, fluid under pressure is admitted to the cylinder at the top side of the piston.

When fluid is admitted to the cylinder at the underside of the piston, piston rod 54 moves upwardly carrying with it frame 53; and if the fluid is admitted to the cylinder at the top side of the piston the piston rod moves downwardly carrying the frame with it. As will be apparent from Fig. 1, upward and downward movements of frame 53 are

utilized to shift the position of the damper connected thereto.

In order that movements of beam 36 may be utilized to operate valve 56, a connecting rod 59 is provided, which, operating through lever 60, bell crank 61, connecting link 62 and stem 58, actuates the valve. If connecting rod 59 moves upwardly, lever 60 is turned in a counter-clockwise direction whereby valve stem 58 is moved downwardly. Downward movement of connecting rod 59 results in upward movement of the valve stem.

If valve stem 58 has been moved downwardly so as to admit fluid to the cylinder at the underside of the piston, frame 53 will move upwardly. In order that the valve may be returned to its closed position when the frame 53 has moved a predetermined distance, an angling bar 64, carried by frame 53, and a lever 65 are provided. Angling bar 64 is pivotally mounted medially of its ends on a bracket 66 carried by frame 53. The upper end of bar 64 may be secured in a yoke 67 by means of a wing nut 68. In order that the angle to which bar 64 is inclined may be adjusted, an adjustment screw 69 is provided. By loosening wing nut 68 and turning screw 69 into or out of the yoke, bar 64 may be turned about its pivotal support in bracket 66 to the proper angle. When adjusted to the proper angle, the wing nut is tightened to securely hold the bar in its adjusted position.

Bar 65 is pivotally mounted at its lower end in a bracket 71 carried at the lower end of cylinder 52. The upper end of bar 65 carries rollers 72 disposed on opposite sides of the angling bar 64. Therefore, as frame 53 moves up or down, carrying with it angling bar 64, lever 65 will turn about its pivotal support. If the frame 53 moves upwardly, bar 65 will be turned in a clockwise direction; and in a counter-clockwise direction if the frame moves downwardly.

Bar 65 is connected to bell crank 61 by a link 73 which is moved to the right when bar 65 turns in a clockwise direction and to the left if the bar is turned in a counter-clockwise direction.

If valve 56 has been opened to admit fluid pressure to the underside of the piston in cylinder 52, frame 53 will move upwardly causing angling bar 65 to turn in a clockwise direction as aforesaid, carrying with it link 73. Movement of the link 73 to the right causes bell crank 61 to turn in a counter-clockwise direction moving valve stem 58 upwardly and closing the valve, whereby the pressure to the cylinder is shut off. If the valve is again opened to admit pressure to the underside of the piston, frame 53 will move upwardly a predetermined distance before the valve is closed again. The length of travel of frame 53 is determined by the rate of closing of the valve when the frame is moving in one direction or the other; and the

rate of closing of the valve is controlled by the angle to which angling bar 64 is adjusted.

If frame 53 is moving in a downward direction in response to successive openings of valve 56, angling bar 64 acting through bar 65 and link 73 will cause the valve to close when the frame has traveled a predetermined distance after each opening of the valve.

From the above, it will be apparent that frame 53 may be caused to move in incremental steps in either direction throughout the full stroke of the piston rod 54.

As shown in Fig. 2 of the drawings, the bellows 19 is mounted on the framework of regulator 17. The lower end of the bellows is connected by a link 76 to beam 36. Therefore, as the pressure admitted to the bellows through pipe line 38' increases or decreases, the bellows will expand or contract, as the case may be, and impose a turning force upon the beam. By properly adjusting the mechanism which operates valve 29, bellows 19 may be caused to act on beam 36 in the same direction as the force of the suction pressure in float or inverted bell 39 acts on the beam. In other words, beam 36 may be caused to move in response to the difference of the forces imposed thereon by the bellows 19 and the pressure acting on float 39.

In practice, it may be desirable to have beam 36 in a condition of stable equilibrium when certain conditions exist in the steam header H and induced draft conduit 14. To place beam 36 in equilibrium, when such conditions exist, a counterweight 77 may be mounted on beam 36 at the opposite side of fulcrum 37 from which float 39 and bellows 19 act on the beam.

Since circuit controlling devices 11 and 11' are similar in construction, the same reference characters will serve to identify like or similar parts.

Circuit controlling device 11' comprises stationary contact members 78, 79 and a yieldably movable contact member 80, that are secured to a block 81 of insulating material. Block 81 is mounted on a bar 82, the opposite ends of which are substantially L-shaped. Bar 82 is frictionally held in friction blocks 83 carried by framework 84 of regulator or motor 35.

In order that bar 82 may be bodily moved when regulator frame 53 has moved in the upward direction, a predetermined distance, a bracket 85 having an adjustable stop 86 is provided and secured to frame 53. When frame 53 has moved upwardly a predetermined distance, the adjustable stop 86 engages the upper L-shaped end of bar 82 and moves it bodily upwards whereby circuit controlling device 11' is bodily moved upwards. The length of travel required of frame 53 before bar 82 is moved upwardly may be ad-

justed by shifting the adjustable stop 86 up or down in the bracket 85.

In order that bar 82 may be moved downwardly when regulator 53 has moved a predetermined distance, a bracket 87 is secured to regulator frame 53 and carries an adjustable stop 88 which is disposed to cooperate with the lower L-shaped end of the bar. Therefore, when regulator frame 53 has moved downwardly a predetermined distance bar 82 will be moved downwardly carrying with it circuit controlling device 11'.

As will be observed from Fig. 2 of the drawings, one end of yieldable contact member 80 is rigidly secured to block 81 and carries a roller 89 at its free end. Roller 89 is disposed in the path of movement of cam blocks 90 carried by regulator frame 53. Blocks 90 are so arranged that when frame 53 has moved a predetermined distance in the upward direction, the lower block will engage roller 89 and cause contact member 80 to contact with contact member 78. Likewise, if frame 53 is moved downwardly a predetermined distance, upper block 90 will engage roller 89 and cause contact member 80 to engage contact member 79.

If the furnace suction, as measured in the furnace uptake 14 decreases, float 39 will rise thereby moving valve operating rod 59 downwardly. Downward movement of rod 59 causes valve 56 to be shifted to that position in which regulator frame 53 will be moved downwardly. As the regulator frame moves downwardly, the induced draft damper 15 will be shifted towards its wide open position. After the frame has moved downwardly a predetermined distance, upper block 90 will close contact members 79 and 80, thereby to increase the speed of fan motor 13. If the suction in the furnace uptake is not restored to normal by such increase in fan speed and increased opening of damper 15, the regulator frame 53 will move downwardly until lower stop 86 engages the lower L-shaped end of bar 80 and move circuit controlling device 11' downwardly to a lower position. During such downward movement, contact members 79 and 80 are held closed, thereby causing the induced draft fan motor 13 to increase its speed as damper 15 is being opened.

If such increased fan speed and increased damper opening has increased the suction in uptake 14 to a value slightly above that required, float 39 will move downwardly whereby valve 56 will be shifted to that position in which frame 53 will be moved upwardly to close damper 15.

The moment regulator frame 53 moves upwardly, contact is broken between contact members 79 and 80, but contact therebetween is broken at a lower point in the travel of the regulator than that at which contact was originally made. The electric control circuit being broken between contact members 79 and

80, the speed of motor 13 driving fan 12 will not be further increased, although the motor will continue to operate at that speed at which it was operating before contact was broken between contact members 79 and 80.

If the suction in the furnace uptake continues to increase above that required, regulator frame 53 will continue to move upwardly and gradually close damper 15. When, in the upward travel of frame 53, lower block 90 engages roller 89 and closes contact members 78 and 80, a control circuit is established that operates to decrease the speed of motor 13 and fan 12. If the suction is still too high, frame 53 will continue to move upwardly to close damper 15 and when it has moved a predetermined distance, upper stop 86 engages the upper L-shaped end of bar 80 and carries device 11' bodily upwards to a higher position.

Thus, the moment the frame starts downwardly, contact members 79 and 80 will be disengaged, but the fan motor will continue to operate at the speed it had attained before these contact members were separated. It is to be noted, that when contact members 79 and 80 are disengaged, the circuit controlling device 11' occupies a higher position than that at which contact was made therebetween at the beginning of the upward stroke of regulator frame 53.

Thus, it will be apparent that when frame 53 is moving in one direction and contact is made either between contact members 79-80 or 78-80, and the frame continues to move in that direction, the circuit controlling device 11' will be shifted bodily in the same direction. Therefore, when the motion of the regulator frame is reversed, the contact members which were closed will be opened when the regulator frame has moved only a relatively short distance in the reverse direction. Therefore, it will be apparent that the circuit control device 11' is always shifted to such a position that contact between either contact member 79-80 or 78-80 is always broken at a point in the stroke of the regulator which is removed from the point in the regulator stroke at which contact was originally made.

It will be understood that each time valve 56 is opened either to cause the regulator frame to move upwardly or downwardly, angling bar 64 and link 73 operate on bell crank 61 in such a manner as to close the valve when the regulator frame has moved a predetermined distance. By so controlling valve 56, regulator frame 53 will move step-by-step in one direction or the other depending upon the position to which the valve is actuated.

If the general movement of frame 53 is upward, contact will be made and broken intermittently between contact members 78 and 80.

Likewise, if the general movement of frame 53 is downward in response to lower-

ing movements of bell 38, either because of a reduction in pressure within the bell or because of increased pressure in bellows 19, the circuit through contact members 79 and 80 ⁵ will be made and broken intermittently.

The operation of the system embodying devices 17 and 9 may best be understood by reference to Figs. 1 and 3 in connection with the following description of the operation of ¹⁰ the system.

Fig. 3 of the drawings illustrates schematically the control system for one of the blower motors 5 and 13 shown in Fig. 1, it being understood that each blower motor is provided with the same type of control system. ¹⁵

For a given load demand on the furnace shown in Fig. 1, regulating devices 9 and 17 are so adjusted that the proper amount of air is supplied to the furnace to satisfy combustion requirements. ²⁰ Also regulators 9 and 17 are so arranged that a substantially constant pressure may be maintained in the furnace combustion chamber. When the pressure in the combustion chamber varies from this constant value, device 9 responds and ²⁵ operates damper 8 to a predetermined position to permit the proper amount of air to pass into the furnace. Device 9 also operates to adjust the speed of the blower motor 5 to such a value that blower 4 will deliver that ³⁰ amount of air which can be effectively changed or regulated by a small change or adjustment in position of the damper.

If, for example, the load demand on the ²⁵ furnace is such that a reduction in pressure within the furnace takes place, bell 38 of regulator 9 will lower, causing frame 53 to lower in the manner aforesaid. As frame 53 moves downwardly, damper 8 is shifted towards the open position. When the frame lowers, upper block 90 will close contact members 79 and 80 causing motor regulator 6 to operate and increase the speed of motor ¹⁰ 5 and the fan or blower 4. The increased speed of the blower is such that the amount of air passing damper 8 may be regulated effectively in response to small changes in position of the damper. ¹⁵

If the position to which damper 8 has been ²⁰ moved is such that the pressure in the furnace is increased, float 38 will rise. Regulator frame 53 will, therefore, move upwardly opening contact members 79 and 80. Motor 5, however, will continue to operate at the aforesaid increased speed. ²⁵

When the pressure in the furnace rises above the value to be maintained therein, float 38 will rise to a higher position and regulator frame 53 will move upwardly in the manner aforesaid thereby closing damper 8 in proportion to the amount that the frame 53 is moved. If the frame moves upwardly a predetermined distance, contact will be made between contact members 78 and 80 ³⁰ whereby motor regulator 6 will operate to

reduce the speed of motor 5. At this reduced speed blower 4 will deliver that amount of air which can be effectively regulated by small changes in position of the damper 8. ³⁵

From the above description, it will be apparent that for each change in position of damper 8, the speed of blower 4 will be changed in the same direction as the direction of movement of the damper. It will be apparent also from the description of Fig. 2, that regulator frame 53, when moving a predetermined amount in either direction, will move the circuit controlling device 11 to a certain position. Therefore, for each position of frame 53, there will be a definite damper position and blower speed. ⁴⁰

By the particular construction of the regulator, it is possible for contact to be made intermittently between contact members 78 and 80 and 79 and 80 without moving bar 82 which carries the circuit controlling device. Thus, for any given position to which damper 8 may be moved, the speed of the blower 4 may be increased or decreased by predetermined amounts without changing the position of the circuit controlling device. ⁴⁵

If damper 8 is moved to approximately its closed position, the speed of blower 4 will be lowered to such a value that the quantity of air passing the damper may be regulated effectively even though the damper is shifted only a relatively small amount. Likewise, if the damper has been actuated to approximately its wide open position, the speed of blower 4 will be increased to such an extent that the volume of air flowing past the damper may be effectively regulated even though the damper is moved only a relatively small amount. And for each intermediate damper position there will be an intermediate blower speed corresponding to the position of the damper. ¹⁰⁰ ¹⁰⁵

In Fig. 3, the circuits and apparatus employed for controlling blower motor 5 are diagrammatically illustrated. As shown, field winding F of motor 5 is connected in series with a resistor 92 across supply conductors 93 and 94. The speed of motor 5 may be increased or decreased by bridging or shunting sections of the resistor. For the purpose of shunting the resistor, a drum 95 may be employed that is driven by a motor 96 through gearing 97. ¹¹⁰ ¹¹⁵

Motor 96 may be of the simple split-field-type reversible motor. For purposes of illustration, motor 96 is provided with field windings 98 and 99. ¹²⁰

When field winding 98 is energized and the armature of the motor is connected across the supply conductors, the motor will operate in such a direction that drum 95 will be moved in the direction of arrow 100. The drum, moving in this direction, will bridge or shunt a section or sections of the resistor thereby ¹²⁵ ¹³⁰

decreasing the resistance in series with field winding F and decreasing the speed of motor 5.

If field winding 99 is energized motor 96 will operate in the opposite or reverse direction, in which case drum 95 will be moved in direction of arrow 101. The drum, moving in this direction, will insert a section or sections of the resistor in series with field winding F of motor 5 thereby weakening the magnetic field of the motor. The speed of the motor will, therefore, be increased.

If regulator frame 53 is moving in the upward direction and contact is made between contact members 78 and 80, a circuit is established whereby a solenoid 102 of a time delay relay 103 is energized. Upon the closure of this relay, solenoids 104 and 105, respectively, of contactors 106 and 107 are energized. Upon the energization of these solenoids, contactors 106 and 107 will close, connecting field winding 98 and the armature of motor 96 across supply conductors 93 and 94. Drum 95 will then be advanced in the direction of arrow 100 to decrease the speed of blower motor 5, because the current in field winding F of motor 5 is increased.

In order that the energizing circuit for solenoids 104 and 105 may be maintained for a predetermined length of time to insure that motor 96 will operate long enough to bridge or shunt at least one section of resistor 92 in series with field winding F, time delay relay 103 is provided with a spring loaded dash pot 109.

Solenoid 102 of relay 103 is controlled by contact members 78 and 80; but when this relay is closed, a circuit is established shunting contact members 78 and 80 and connecting solenoids 104 and 105 across supply conductors 93 and 94. Therefore, if, after contact has been made between contact members 78 and 80, contact should be momentarily broken therebetween, solenoids 104 and 105 will remain energized for a predetermined length of time, the length of time being determined by the length of time required for the spring loaded dash pot 109 to open the contact members of time delay relay 103.

From the above, it will be observed that if the general movement of regulator frame 53 is upwards and momentary contact is made and broken intermittently between contact members 78 and 80, motor 96 will be energized intermittently. Each time the motor is energized, it will operate for such a length of time that at least one section of resistor 92 will be bridged or shunted out of the circuit of field winding F of motor 5. Therefore, the speed of motor 5 will be decreased step-by-step as damper 8 is closed step-by-step by the regulator or device 9.

If the pressure in the furnace is decreasing below the value to be maintained therein, float 39 will lower and move connecting rod

59 downwardly. As stated previously herein, downward movement of rod 59 causes valve stem 62 to move upwardly whereby fluid under pressure is admitted to the cylinder 52 at the top side of the piston therein. Frame 53 will then move downwardly a predetermined distance and will come to rest when the angling bar 64 has operated to close the valve.

If the distance which frame 53 has moved downwardly is not great enough to cause contact members 79 and 80 to close, motor 5 will continue to operate at that speed at which it was operating before the regulator moved downwardly. However, damper 8 will be opened to permit more air to flow to the furnace.

If the downward movement of frame 53, however, is great enough to cause contact members 79 and 80 to close, a circuit will be established for energizing a solenoid 110 of a time delay relay 111. Upon the closure of relay 111, solenoids 112 and 113 of contactors 114 and 107 are connected across supply conductors 93 and 94. Contactors 114 and 107 will, therefore, close to connect field winding 99 and the armature of motor 96 across the supply conductors 93 and 94. Motor 96 will then operate in such a direction as to move drum 95 in the direction of arrow 101, thereby to insert a section or sections of resistor 92 in series with field winding F of motor 5.

The current in field winding F will therefore be decreased and motor 5 will operate at increased speed. From the above it will be observed that damper 8 has been opened a predetermined amount. It will also be observed that the speed of motor 5 has been increased an amount depending upon the amount that damper 8 was opened.

In order to insure that contactors 114 and 107 will remain closed for such a length of time that at least one section of resistor 92 will be inserted in series with the field winding F of motor 5, time delay relay 111 is provided with a spring loaded dash pot 115.

The energization of solenoid 110 of relay 111 is controlled by contact members 79 and 80, but the energization of solenoids 112 and 113 of contactors 114 and 107 is controlled by the contact members of relay 111. Therefore, the moment contact members 79 and 80 are closed, solenoid 110 will be energized to close relay 111 whereby a circuit is established through the contact members of this relay for energizing the solenoids of contactors 114 and 107. Contactors 114 and 107 will remain closed for a predetermined length of time and is determined by the time characteristic of dash pot 115. Dash pot 115 is arranged to open the contact members of time delay relay 113 when the time period has elapsed and this period should be sufficient to permit motor 96 to operate until at least one section of resistor 92 has been inserted in series with the field winding F of motor 5.

If the pressure in the furnace falls still lower, indicating that more air is required for combustion, float 39 will lower still further causing the frame 53 to move downwardly. As the frame moves downwardly, contact will be made between contact members 79 and 80, and motor 96 will be caused to operate and drive drum 95 in the direction of arrow 101 with the result that motor 5 will be speeded up. The increased speed of motor 5 will be in accordance with the new position to which damper 8 has been moved. If regulator frame 53 has been moved downwardly a predetermined amount, stop 88 will engage the lower L-shaped end of bar 82 whereby circuit controlling device 11 is moved bodily downward to a position corresponding to the position of the regulator frame. The circuit controlling device 11 will, therefore, be in such a position that for small movements of regulator frame 53 in either the upward or the downward direction, the speed of motor 5 may be increased or decreased in accordance with relatively small movements of damper 8 either to its closed or open position. In any event each time regulator frame 53 has moved downwardly a predetermined distance, bar 82 will be moved downwardly and carry with it circuit controlling device 11 to a different position. By causing circuit controlling device 11 to move bodily with the regulator after it has moved a predetermined distance, the speed of motor 5 may be increased step-by-step as damper 8 is opened step-by-step.

Regulator 17 operates to control the position of damper 15 and the speed of blower motor 13 in the same manner as regulator 9 operates to control the position of damper 8 and the speed of blower motor 5. However, regulator 17, as stated hereinbefore, is affected both by the pressure in duct 14 and the demand for steam upon header H of the boiler. If the demand for steam on header H remains constant, then variations in pressure in duct 14 will cause variations in pressure within inverted bell 39 and the regulator will respond to either increase or decrease the speed of motor 13 in the same manner as regulator 9 operates to either increase or decrease the speed of motor 5.

If at any particular time the position of damper 15 is such as to satisfy the combustion conditions within the furnace, but a demand for steam on header H is such that more combustion will be required in the furnace, then valve 21 will be operated in the manner hereinbefore described to decrease the pressure in bellows 19 causing inverted bell 39 to move upwardly. As the bell moves upwardly, the regulator frame 53 will be caused to move downwardly to open damper 15 and to increase the speed of motor 13. In any case if the regulator 17 is caused to operate damper 15 to a different position, the

speed of motor 13 will be caused to change in the same direction as the damper is shifted or moved. The speed of motor 13 will follow the change in position of damper 15 whether such change be caused by variations in pressure in duct 14 by changes in pressure in header H or both. Bell 38 will come to rest and be in equilibrium with bellows 19 when the pressure in duct 14 has increased the proper amount in response to the increase in fan or blower speed.

From the above it will be apparent to those skilled in the art that a system for controlling the speed of a blower in accordance with the position of a damper regulating the flow of air produced by the blower is disclosed. This system as described operates to change the blower speed step-by-step as the position of the damper is changed step-by-step. The system is so arranged that the amount of air flowing past the damper will be such that an appreciable change in the flow of air may be affected by only a small change in the damper position.

While various modifications and changes may be made in the invention as disclosed without departing from the spirit and the scope thereof, it is to be understood that only such limitations shall be placed on the invention as are imposed by the prior art and the appended claims.

What I claim as new and desire to secure by Letters Patent is:

1. In combination with a boiler furnace having forced and induced draft fan blowers, a damper associated with each blower, a driving motor for each blower, a regulator responsive to furnace pressure for actuating the forced draft blower damper, means controlled by said regulator for controlling the speed of the forced draft blower motor in accordance with the position of the forced draft damper, a regulator responsive to the demand for steam for actuating said induced draft damper, and means controlled by said steam demand regulator for regulating the speed of the induced draft fan motor in accordance with the position of the induced draft damper.

2. In combination, actuating means, a pressure actuated device controlled by said actuating means, a plurality of circuit controlling members, means operable by said actuated device for bodily moving said circuit controlling members, and means for holding said controlling members in any position to which they may be moved by said pressure actuated device.

3. In combination, actuating means, a pressure regulator controlled by said actuating means, said regulator having a movable member actuated thereby, an electric circuit controlling device, means for bodily moving said circuit controlling device in response to movements of said movable member, and

- means holding said circuit controlling device in any position to which it is actuated.
4. In combination, a device having a movable member actuated by pressure, a circuit controlling device having means actuated by said movable member for bodily moving said circuit controlling device, and means for holding said circuit controlling device in any position to which it may be actuated.
- 10 5. In combination, a regulator having a movable member actuated by pressure, a circuit controlling device arranged to be operated by said regulator and to be bodily moved thereby when said movable member has travelled a predetermined distance.
- 15 6. In combination, a regulator having a movable member actuated by pressure, a circuit controlling device arranged to be operated by said regulator and to be bodily moved thereby when said movable member has travelled a predetermined distance and means for holding said circuit controlling device in any position to which it may be moved.
- 20 7. In combination, a regulator having a movable element actuated by pressure, means for causing said element to move in incremental steps, an electric circuit controlling device, and means operatively connecting said movable element and device disposed to effect successive movements thereof in response to predetermined increments of movement of said element.
- 25 8. In combination, actuating means, an element actuatable by pressure controlled by said means, a circuit controlling device arranged to be actuated by said element to one circuit controlling position when said element is moving in one direction and to another circuit controlling position when moving in the opposite direction, and means operatively connected to said element and device for changing the points in the travel of said element at which the device is actuated to said circuit controlling positions.
- 30 9. In combination, a regulator having a movable member arranged for movement in accordance with a condition to be controlled, a circuit controlling device arranged to be operated by said member in response to a predetermined movement thereof, and means for so modifying the operative relation of said device and movable member that the device may be operated at different points in stroke or travel of said movable member in response to predetermined movements of said member throughout the full range of travel or stroke thereof.
- 35 10. In combination, a regulator having a movable member arranged for movement in accordance with a condition to be controlled, a circuit controlling device arranged to be operated by said member in response to a predetermined length of movement thereof, and means for causing said device to be operated at different points in the stroke of said
- movable member in response to predetermined movements of said member throughout the full range of travel or stroke thereof.
11. In combination, actuating means, a pressure regulator controlled by said actuating means, an electric circuit controlling device actuated by said regulator at a definite point in the stroke of the regulator, and means actuatable by the regulator for changing the point in the stroke thereof at which said device is actuated.
- 70 12. In combination, actuating means, a regulator controlled by said actuating means, an electric circuit controlling device having a lost motion connection with and adapted to be operated in response to a definite movement of the regulator, and means operated by the regulator for changing the point in the stroke of the regulator at which said device is operated when the movement of the regulator exceeds the limits of the lost motion permitted by the connection.
- 75 13. In combination, a regulator, two circuit controlling devices separately actuatable by said regulator, said devices being so disposed that the regulator must travel a distance in one direction or another sufficient to have operative connection therewith before one or the other of said devices is actuated thereby, and means operated by the regulator for concurrently displacing the points in the stroke of said regulator at which operative connection is made with said devices when the movement of the regulator has exceeded the amount required to connect and operate said devices.
- 80 14. In combination, a regulator, two circuit controlling devices separately actuatable by said regulator, said devices being so separated that the regulator must travel a predetermined distance in one direction or another before one or the other of said devices is actuated thereby, and means wholly dependent on movements of the regulator for concurrently displacing the points in the stroke of the regulator at which said devices are actuated thereby.
- 85 15. In combination, a regulator having an element adapted to move in one direction or another between two extreme positions in response to and in accordance with changes in a variable to be controlled, a circuit controlling device adapted to be operated to one circuit controlling position, when said element has moved a predetermined distance in one direction and to another circuit controlling position when said element has moved a predetermined distance in the opposite direction, and means adapted to change the points in the travel of said element at which said device is operated to one or the other of its controlling positions when said element has moved a distance greater than said predetermined distance in either direction.
- 90 16. In combination, a regulator having an element adapted to move in one direction or another between two extreme positions in response to and in accordance with changes in a variable to be controlled, a circuit controlling device adapted to be operated to one circuit controlling position, when said element has moved a predetermined distance in one direction and to another circuit controlling position when said element has moved a distance greater than said predetermined distance in either direction.
- 95 17. In combination, a regulator having an element adapted to move in one direction or another between two extreme positions in response to and in accordance with changes in a variable to be controlled, a circuit controlling device adapted to be operated to one circuit controlling position, when said element has moved a predetermined distance in one direction and to another circuit controlling position when said element has moved a distance greater than said predetermined distance in either direction.
- 100 18. In combination, a regulator having an element adapted to move in one direction or another between two extreme positions in response to and in accordance with changes in a variable to be controlled, a circuit controlling device adapted to be operated to one circuit controlling position, when said element has moved a predetermined distance in one direction and to another circuit controlling position when said element has moved a distance greater than said predetermined distance in either direction.
- 105 19. In combination, a regulator having an element adapted to move in one direction or another between two extreme positions in response to and in accordance with changes in a variable to be controlled, a circuit controlling device adapted to be operated to one circuit controlling position, when said element has moved a predetermined distance in one direction and to another circuit controlling position when said element has moved a distance greater than said predetermined distance in either direction.
- 110 20. In combination, a regulator having an element adapted to move in one direction or another between two extreme positions in response to and in accordance with changes in a variable to be controlled, a circuit controlling device adapted to be operated to one circuit controlling position, when said element has moved a predetermined distance in one direction and to another circuit controlling position when said element has moved a distance greater than said predetermined distance in either direction.
- 115 21. In combination, a regulator having an element adapted to move in one direction or another between two extreme positions in response to and in accordance with changes in a variable to be controlled, a circuit controlling device adapted to be operated to one circuit controlling position, when said element has moved a predetermined distance in one direction and to another circuit controlling position when said element has moved a distance greater than said predetermined distance in either direction.
- 120 22. In combination, a regulator having an element adapted to move in one direction or another between two extreme positions in response to and in accordance with changes in a variable to be controlled, a circuit controlling device adapted to be operated to one circuit controlling position, when said element has moved a predetermined distance in one direction and to another circuit controlling position when said element has moved a distance greater than said predetermined distance in either direction.
- 125 23. In combination, a regulator having an element adapted to move in one direction or another between two extreme positions in response to and in accordance with changes in a variable to be controlled, a circuit controlling device adapted to be operated to one circuit controlling position, when said element has moved a predetermined distance in one direction and to another circuit controlling position when said element has moved a distance greater than said predetermined distance in either direction.

16. In combination, a regulator having an element adapted to operate between two extreme positions, a circuit controlling device adapted to be actuated by said regulator element when it has moved a fractional part of its total travel towards one or the other of said positions, and means for maintaining the said fractional-travel relationship between the circuit controlling device and the regulator throughout the full travel thereof. 70
17. In combination, a regulator having a movable element adapted to operate between two extreme positions, a circuit controlling device having at least two circuit controlling positions, said device having a connection with said regulator element adapted to actuate said device to one of its controlling positions, when the regulator element has moved a fractional part of its total travel in one direction, and to the other circuit controlling position when the regulator element has moved a fractional part of its travel in the opposite direction, and means for maintaining said fractional-part travel relationship between said regulator element and device independently of the position of said element. 80
18. In combination, a regulator having an element adapted to operate between two extreme positions, circuit controlling devices adapted to be actuated by said regulator element at points separated a distance equal to a fractional part of the total travel thereof, and means controlled by movement of the regulator for maintaining said fractional-part travel relationship between said devices and regulator throughout the full stroke thereof. 90
19. In combination with a boiler furnace having forced and induced draft fan blowers, a damper associated with each blower, a driving motor for each blower, a regulator responsive to furnace pressure for actuating the forced draft blower damper, means controlled by said regulator for controlling the speed of the forced draft blower motor in accordance with the position of the forced draft damper, and a regulator responsive to the demand for steam for actuating said induced draft damper. 100
20. In combination with a boiler furnace having forced and induced draft fan blowers, a damper associated with each blower, a driving motor for each blower, a regulator responsive to furnace pressure for actuating the forced draft blower damper, a regulator responsive to the demand for steam for actuating said induced draft damper, and means controlled by said steam demand regulator for regulating the speed of the induced draft fan motor in accordance with the position of the induced draft damper. 110
21. In combination with a duct having a damper therein, a fan blower connected to the duct, an adjustable speed motor for driving the fan blower, and apparatus for con- 115
